E. H. RICHTER

CLARIFIER

Filed April 6, 1925

The technical drawing illustrates a vertical shelving unit, likely a bookshelf or display case. The unit is composed of two main vertical panels, each featuring a series of horizontal shelves. The left panel is labeled with reference numbers 5, 8, 9, 10, and 11. The right panel is labeled with reference numbers 6, 7, 8, 9, 10, and 11. A central vertical support column is labeled with reference numbers 10 and 12. The bottom of the unit features a base with a decorative scalloped pattern, labeled with reference number 11. The entire structure is enclosed within a rectangular frame.

UNITED STATES PATENT OFFICE.

ERNEST H. RICHTER, OF SEATTLE, WASHINGTON.

CLARIFIER.

Application filed April 6, 1925. Serial No. 20,922.

My invention relates to clarifiers and the principal objects of the invention are to provide a vessel with a plurality of shelves superimposed one upon the other in spaced relation by means of connecting conduits that form a continuous passageway from the bottom to the top of the vessel whereby the clarified liquid may be siphoned off after the sediment has collected on the shelves. Further objects are to provide a clarifier by means of which the clarification of liquids is considerably accelerated, that is simple and durable in construction, reliable and efficient in operation, which may be readily cleaned, and which may be manufactured at comparatively small cost.

With the above and other objects in view which will appear as the description proceeds, the invention consists of the novel construction, adaptation, combination and arrangement of parts hereinafter described and claimed. These objects are accomplished by devices illustrated in the accompanying drawings, wherein—

Figure 1 is a view in central vertical section of a clarifier embodying the features of the invention; and

Fig. 2 is a view in horizontal section taken substantially on a broken line 2, 2 of Fig. 1.

Referring to the drawings throughout which like reference numerals designate like parts, the numeral 5 indicates a vessel having a removable cover 6. The numeral 7 designates a plurality of shelves mounted within said vessel in spaced relation as shown in Fig. 1. Said shelves are slightly smaller than the vessel whereby spaces 8 are provided on the sides, and perforations 9 are provided through the shelves for reasons presently set forth.

Each of the shelves 7 is provided with a central conduit 10 fixedly secured thereto and projecting above and below. I prefer to make such conduits slightly conical in shape so that they may nest one within the other to form substantially air tight connections. It will also be noted that their lower ends are tapered to form sharp edges in order to obviate shoulders which would obstruct the free upward passage of liquid.

As clearly shown in Fig. 1 of the drawings, the conduits 10 fit one within the other thus forming a continuous passageway. The lowermost shelf 7 is supported above the bottom of the vessel 5 by legs 11 resting thereon and in such position that the lower end of its conduit 10 is at a distance above the bottom of the vessel. A siphon 12 may extend through the cover 6 and fits snugly within the uppermost conduit.

In the operation of my device the liquid is poured into the vessel and passes downwardly through the spaces 8 and perforations 9. Upon standing for a time the sediment within the liquid will gravitate downwardly to the particular shelf that is directly below. It will be apparent that the short distance which the sediment travels before coming in contact with a shelf will materially hasten the process of clarification. It will also be obvious that most of the sediment will be caught on the shelves and therefore the bottom of the vessel from whence the liquid is siphoned will be comparatively free from dregs.

After sufficient clarification has taken place the liquid is siphoned off, passing upwardly through the passageway formed by the connecting conduits 10, and as the liquid is lowered the shelves will intercept any additional sediment that may be held in suspension. The shelves may be readily removed and cleaned as will be readily understood.

Each of the shelves 7 is a unit within itself and it will be understood that any desired number may be used by extending the siphon 12 downwardly to fit within the uppermost conduit. Said shelves may be made any shape or size to conform to the shape of the vessel used.

While I have described my device in considerable detail, it will be understood that I intend no limitations except in so far as may be imposed by the appended claim, and that such changes may be resorted to as are within its scope and spirit.

Having thus described my invention what I claim and desire to secure by Letters Patent is:

55
60

65

70
75

75

80

85

90

95

100

A clarifier comprising a vessel, a plurality of shelves, each of said shelves having a conduit, each of said conduits arranged to fit one within the other to form a continuous passageway, said conduits adapted to retain said shelves in superimposed spaced relation, means for supporting the lowermost shelf

and its conduit above the bottom of the vessel, and means for connecting a siphon to the uppermost conduit.

10

In witness whereof, I hereunto subscribe my name this 25th day of March, A. D. 1925.

ERNEST H. RICHTER.
